LADY'S GARMENT

Harriet S. Kohler, Larchmont, N. Y., and
Frances R. MacKinnon, Westport, Conn.

Application September 23, 1935, Serial No. 41,646

5 Claims. (CL. 2—73)

This invention relates to improvements in ladies' garments and relates more particularly to an improved undergarment of the variety known as a "slip" and also to the method of making same.

In recent years, the designers of ladies' slips and the like have cut the material on the bias in an effort to cause the garment to cling more closely to the body than was possible with the older type of straight cut garment. In so cutting the material on the bias, the garment became possessed of greater elasticity and resiliency, thereby making for a more comfortable garment, particularly when one is sitting down.

Another advantage of the bias cut garment is in the fact that a garment of any given size will fit a larger variety of figures than would the straight cut garment, since the material yields more readily to the shape of the body regardless of the position in which one is sitting or standing. One of the principal objections to this type of garment is in the fact that when one sits down, the central portions yield outwardly to accommodate the increased girth and this expansion is compensated for by the lower end of the garment "riding" upwards, and the upper end of the garment being pulled downwardly, with a resulting strain upon the shoulder straps. Another objection to the bias cut garment is in the fact that unless one is sitting perfectly straight, the pull becomes uneven, thereby giving the wearer a feeling of strain. For the most part, however, the bias cut slip is more comfortable than the straight cut garment, and the construction of this type of garment requires considerably less material than does the straight cut type, which is a factor for the manufacturer.

The straight cut type of garment, however, also has its several disadvantages. In the first place, in order to cause the central portions of the garment to fit sufficiently snugly, a seam is normally provided on each side of the garment, which is both uncomfortable to the wearer and is noticeable, particularly when a rather tightly fitting outer garment is worn. Also, compared to the bias cut garment, the amount of resiliency is very small and accordingly the garment is far less comfortable. Furthermore, it is obvious that a considerably greater amount of material is employed, since the material should be as wide as the widest portion of the garment at the lower end, thereby resulting in a considerable waste of goods.

It is one of the principal objects of the present invention to provide an improved garment

of the straight cut variety, which garment normally employs the full width of the material, the central vertical line of the goods occupying the position at the front central portion of the body. The garment is constructed entirely in one piece except for a relatively small triangular portion, or godet, which is fitted into the lower rear portion thereof. Although the horizontal grain line of the goods occupies a generally horizontal position in the finished garment, the cloth is nevertheless so shaped and molded by means of a plurality of darts of improved construction that the waist portions of the garment have a decidedly bias play. In other words, by arranging the darts in the proper fashion, the grain line of the goods around the waist to lower hip portions of the garment is changed from a true horizontal position to an angle something in excess of 30° thereto. The darts are of a tapered variety, being more narrow adjacent to the front central portion of the garment and assuming a greater width as they move towards the rear of the garment. The number of darts may vary, depending upon the precise shape of the figure to be fitted. In general, however, two or three such darts are sufficient on each side of the garment.

A garment constructed in the manner herein-after described in greater detail, is provided with only one principal seam, to wit, the vertical seam at the central rear portion of the garment, and two relatively short seams on either side of the godet. The avoidance of the side seams such as are present in virtually all well fitting straight cut garments, gives the present slip a greatly improved appearance and it is also considerably more comfortable to the wearer. The present improved slip also gives to the wearer a vastly improved silhouette, due in no small measure to its capability of always hugging the figure, regardless of what position the body is occupying at the given instant. When one wearing the present improved slip sits, the garment has substantially the same degree of resiliency as the ordinary bias cut slip. It does not, however, "ride" upwards at the lower end, or pull upon the shoulder straps at the upper end. Inasmuch as the material may be of a width corresponding roughly to the circumference of the body, a great saving in material results.

The present invention is not, of course, limited to the provision of an undergarment merely, since an evening dress, night-gown, or any other article of apparel may be constructed in accordance with the present invention. This garment may have as much or as little fullness as desired, with-

out substantially increasing the amount of material used, since when more fullness is desired, it is only necessary to increase the width and/or length of the godet, the body portion remaining the same size.

Another object of the invention is the provision of an improved garment which gives the entire upper front portion of the garment a more form-fitting effect, which effect is preserved intact whether the wearer be sitting down or standing up. As heretofore stated, the customary bias cut garment pulls downwardly at the upper end, thereby straining the shoulder straps, and moves upwardly at the lower end when a person sits down. In the present improved garment, there is virtually no strain at either upper or lower end, and as a result, shoulder straps can effectively be eliminated entirely.

A still further object of the invention is the provision of an improved method for making a garment of the character above referred to, wherein the amount of labor required to construct the garment is substantially less than at present, particularly by virtue of the fact that seams are almost entirely eliminated and the time required in cutting the goods is likewise greatly diminished.

Yet another object of the invention is the provision of an improved garment construction, wherein a variety of necklines may be provided without altering the general structure of the garment.

In the drawings:

Fig. 1 is a side elevation of one of the presently preferred embodiments of the invention, the garment being shown in position upon the body of the wearer;

Fig. 2 is a front elevation thereof;

Fig. 3 is a rear elevation;

Fig. 4 is a plan view of the two blanks of material employed in the construction of the present garment;

Fig. 5 is similar to Fig. 4 which shows the two blanks folded and ready for cutting;

Fig. 6 is a plan view of the two portions of cloth employed in the construction of the present garment, the view showing the cut-out portions in the main body of the garment; and

Fig. 7 is a plan view of the finished garment folded along its front and rear vertical center lines.

The embodiment of the invention which is chosen for illustration in the drawings is a ladies' undergarment, or slip. It will be appreciated, however, that substantially the same directions as herein given may be followed for constructing an evening gown, a tea gown, a night-gown, or other article of wearing apparel. The blank 10 which constitutes the main body of the garment is substantially square and preferably employs the full width of the material. The complete garment, as heretofore stated, is constructed of two pieces of material, the second of which is indicated as 11. The piece is triangular in shape and forms the lower rear portion of the garment and is generally known in the dressmaking art as a godet.

In making the garment, the body portion 10 is first folded along the central vertical line *a—a* (Fig. 4), said line *a—a* forming the front central line of the garment indicated at 12 in Figs. 5 and 7. The broken lines in Fig. 7, which complete the rectangle, show the full blank 10 in its originally folded position, and the line *b—b* therein constitutes the lower edge of this original

blank, designated as 13 in Figs. 4 and 5. A triangular portion is cut from this lower edge, thereby forming the lower edge 14 of the main body of the garment.

A plurality of darts are now formed at the upper end of the main body portion, said darts extending inwardly from the free vertical edges or selvage 16. A dart is defined as a short tapered seam uniting two edges where a piece has been cut away in order to fit the garment to the figure. In the instant case, the darts are desirably formed in the body of the garment prior to the cutting. For the sake of clearness, however, in the plan view in Fig. 6, the cut-out portions are shown as having been formed prior to the stitching. This view actually shows the shape of the blank, however, if the darts were first stitched, then the surplus portions cut from the rear side of the garment and the stitches thereafter removed.

It will be noted from Fig. 6 that the upper edge 17 of the first cut-away portion, although curved, is substantially straight and parallel with the upper edge 18 of the garment. The lower edge 19 of this first cut-away portion is somewhat downwardly inclined with reference to the upper edge 18 of the garment, and is formed with a greater curve than the edge 17, as will be noted. The two horizontal portions 25 and 26 are joined together along the stitch lines 20 and 21 which are parallel with their respective edges. In the event that this cut-out portion be formed prior to the stitching, the edges 17 and 19 would be formed with a plurality of opposed, unaligned notches 22 in substantially the relation shown, and when the two edges are stitched together along the stitch lines 20 and 21, the corresponding notches, as indicated by the broken lines 24, are aligned with each other. In other words, the curved edge 19 is not merely moved directly upwardly to be joined to the edge 17, but rather is eased or pulled towards the rear of the garment. The marginal edge between the stitch line 21 and the edge 19 is folded rearwardly and this entire portion 25 is raised upwardly to be joined to the upper portion 26 along the stitch line 20. In order to join the two edges in the relation indicated by the notched portions 22, it is obvious that the upper portion must be eased towards the front of the garment, and the lower one pulled upwardly and towards the rear of the garment. In other words, the upper edge 17 is longer than the lower edge 19 and they are, as aforesaid, joined together in end to end relationship by having the lower edge under tension during the sewing of the seam, or by having this lower edge free from tension and gradually absorbing or taking up the greater length of the upper edge as the seam is made, thereby providing fullness in one edge relative to the other. Accordingly, in the appended claims, the meeting edges of the darts are described as being "fullled" relative to each other.

The lower edge 27 of the portion 25 is next joined to the upper edge 28 of the portion 29 along the stitch lines 30 and 31 respectively. The degree of the easing and pulling of these darts varies in order to shape it to the bust, waist and hip. In carrying out the present invention, this second dart is normally eased and pulled more than either the first or third. Finally, the lower edge 32 of the portion 29 and the upper edge 33 of the portion 34 are joined together along the stitch lines 35 and 36, respectively. Whereas these darts may be formed in the manner just described, it is nevertheless a more simple opera-

tion to form the stitches in the first instance, since the act of easing and pulling the material is more easily performed than if the cut-out portions were made previously.

5 After the three darts have been placed in the main body of the garment in the manner described, the surplus material in the rear portion thereof is trimmed, and a curved portion cut from the selvage along the line 37. This cut-out portion begins at the point 38, which is substantially one-third of the distance downwardly from the upper end of the blank, and terminates at or near the point 39, which is desirably somewhat below the upper edge 18 of the blank. When the finished body portion of the garment is folded flat along the line 12, it assumes the position shown in Fig. 7 and it is stitched along the line 37. The vertical edge 40 of the portion 26 has been, in effect, moved downwardly to the position shown in Fig. 7. Also, the partially curved and partially straight edge between the points c and d, correspond generally to the previously mentioned cut-away portion 37.

25 The triangular portion or godet 11 is then stitched along its vertical edges 41 to the remaining portion of the selvages 16. Thus, the rear of the garment when in the flat position shown in Fig. 7, presents a straight edge indicated as 42 over the greater portion of its length.

30 It will be noted that the horizontal grain line of the goods at the lower portions of the garment indicated at 43 is, in the upper portion of the garment, changed substantially 30°, as indicated at 44. This latter grain line is, in effect, substantially parallel with the major portion of the upper edge 18 of the garment, which edge, of course, engages the body considerably higher in the front than in the rear. Thus, it will be seen that this grain line is at an angle of approximately 30° from the true horizontal line, thus giving the garment the bias cut effect around the waist and hip portions thereof. As a result of the dart formation, the portions which engage the shoulder blade area are outwardly flared, as indicated at 45, as are the portions 46 which engage the breasts.

45 The upper edge 18 of the garment may be finished with lace or in any other desired manner. Also, a pair of shoulder straps 48 may be provided, although they are not entirely essential.

In the claims the expression "the grain of the central portion of the blank being substantially on the straight" means that either the warp or weft of said central portion extends at right angles to the median line a—a of the blank.

What we claim is:

1. A body garment having waist and skirt portions made from a blank having a central portion and side portions, the grain of the central portion of said blank being substantially on the straight, a plurality of elongated darts extending inwardly and convergently from the side edges of said blank, the side edges being secured together so as to form a waist-encircling portion, the darts extending from the rear of the garment

and through the underarm sections in the waist section of said garment, the material between said darts being disposed on the bias with respect to the front median line of the garment.

2. A body garment having waist and skirt portions made from a blank having a central portion and side portions, the grain of the central portion of said blank being substantially on the straight, a plurality of elongated darts having adjacent edges curved along segments of different circles, said darts extending inwardly and convergently from the rear of each of said side portions towards the central portion of the blank to dispose the threads of the material in the zone of the darts, and the material above and below the same, on a bias with respect to the front median line of the blank, the side portions of each blank being secured together to form a waist-encircling portion, said darts extending from the rear of the garment and through the underarm sections in the waist of said garment.

3. A garment having waist and skirt portions made from a blank having a central portion and side portions, the grain of the central portion of said blank being substantially on the straight, an elongated dart extending inwardly from the rear of each of said side portions towards the central waist portion of the blank, the edges of the dart being so curved along segments of different circles as to dispose the threads of the material in the zone of each dart, and the material above and below the latter on a bias with respect to the front median line of the center portion, the side portions of said blank being secured together to form a waist-encircling portion, each of said darts extending from the rear of the garment and through the underarm sections in the waist of said garment.

4. A body garment having waist and skirt portions, the fabric in the front of said garment being substantially on the straight, each side of said waist portion being provided with an elongated dart which extends from the bust portion to the rear of the garment, a seam joining the edges of said dart, the weave on one side of said seam being in a biased position relative to the weave on the other side of said seam, the meeting edges of the fabric of each dart being of unequal length, the longer edge being fulled relative to the shorter edge.

5. A body garment having waist and skirt portions, the fabric in the front of said garment being substantially on the straight, the waist portion being provided on each side thereof with a dart extending from the front to the rear of the garment, the meeting edges of the fabric of said dart being originally of unequal length, the free ends thereof being joined together and said meeting edges being joined throughout their entire length in order to provide fullness in the bust encircling portion and to provide a progressively increasing bias from front to rear of the waist portion.
